UNITED STATES PATENT OFFICE.

JOHN M. HANSEN, OF PITTSBURG, PENNSYLVANIA, ASSIGNOR TO PRESSED STEEL CAR COMPANY, OF PITTSBURG, PENNSYLVANIA, A CORPORATION OF NEW JERSEY.

BODY-BOLSTER FOR RAILWAY-CARS.

SPECIFICATION forming part of Letters Patent No. 749,133, dated January 5, 1904.

Original application filed December 21, 1900, Serial No. 40,649. Divided and this application filed August 28, 1901. Serial No. 73,612. (No model.)

To all whom it may concern:

Be it known that I, JOHN M. HANSEN, a citizen of the United States, residing at Pittsburgh, in the county of Allegheny and State of Pennsylvania, have invented a certain new and useful Improvement in Body-Bolsters for Railway-Cars, of which the following is a full, clear, and exact description.

This invention relates to bolsters built in 10 with and as a part of the underframe of railway-cars, and more especially freight-cars, and particularly cars for conveying ballast and the like, the last being commonly known as "center-dump ballast-cars," and this case 15 is a division of my application for patent for center-dump ballast-cars, filed December 21, 1900, Serial No. 40,649.

The object of the invention is to construct a body-bolster within and as a part of the underframe, especially of metallic center-dump ballast-cars, the parts being preferably of plate-steel or sheet-steel pressed to shape and assembled by riveting, although other material than pressed steel may be used.

25 The invention consists of a bolster comprising a pair of parallel channelled beams extending continuously between and secured to the side sills and having a cover-plate extending from side to side of the car and from the inner edge of the bolster outwardly toward the end of the car and of greatest width in the plane of the draft-rigging, and a correspondingly-shaped cover-plate applied to the lower edge of the bolster and extending from 30 side bearing to side bearing and also projecting outwardly toward the end of the car and of greatest width in the plane of the draft-rigging, all as I will proceed now more particularly to set forth and finally claim.

40 In the accompanying drawings, illustrating my invention, in the several figures of which like parts are similarly designated, Figure 1 is a top plan view of the underframe with the body omitted from the left-hand end. Fig. 45 2 is a plan view similar to the left-hand end of Fig. 1 and on a larger scale and illustrating another arrangement. Fig. 3 is a longitudinal section taken substantially in the

plane of line A B of Fig. 2. Fig. 4 is a half-section and elevation of the bolster in position in the underframe.

50 The trucks, the couplers, and the air-brake mechanism illustrated in part in Figs. 1 and 2 may be of any approved construction, and therefore need no detailed description in this 55 specification. The underframe comprises side sills 2 and end sills 3 and draft-rigging sills 4, also of approved construction.

55 The body-bolsters are of box-girder type, and the novelty in their construction is as 60 follows: Between the side sills are arranged the transverse channelled beams 5, which constitute the foundation of the body-bolster, and these beams 5 are covered in at top by a plate 6, which is riveted to the upper flanges 65 of the beams 5 and is of greatest width in the plane of the draft-rigging sills 4, the same being also riveted to the flanges of these sills 4 and to the flanges of the side sills 2. Also at the top are applied gusset-plates 7, of triangular outline, and which are riveted to the upper flanges of the inner beam 5 and the upper flanges of the side sills. The ends of the beams 5 are dished at 8 to provide clearance for the wheels, and next to these dished 70 portions are secured the side bearings 9. Between the side bearings and underlying them is the bottom cover-plate 10, of the outline shown by dotted lines, Figs. 1 and 2, and, like the plate 6, extending outwardly and having 75 its greatest width in the plane of the draft-rigging sills. By this construction of top and bottom cover-plates and gussets the under frame, including the bolster, is greatly reinforced to resist the shocks and strains imposed upon this portion of the car.

80 As shown in Fig. 2, the underframe may be further strengthened by the use of oblique braces 11, which diverge from the bolster at the draft-rigging sills toward the angles 90 formed by the junction of the side and end sills, and these junctions may be further reinforced by gusset-plates 12, or, as shown in Fig. 2, these braces (designated 13 in that figure) may diverge from the draft-rigging sills 95 at the end sill inwardly toward the junction

of the bolster with the side sills, and suitable gusset-plates 14 may be arranged in the angles between the draft-rigging sills and the end sills. In either case the oblique braces 5 will be riveted to the top cover-plate and the gusset-plates.

As shown by reference to Figs. 1 and 2, the center sills 15 are out of longitudinal alinement with the draft-rigging sills. These center sills are preferably composed of angle steel or iron, rolled or wrought, and their ends are bolted or riveted to brackets 16, which in turn are secured to the beams forming the bolsters. These center sills are arranged at an incline 15 corresponding to the incline of the bottom of the body, as shown more particularly in Fig. 4.

The underframe thus described is designed, as already intimated, especially for a center-dump ballast-car body, and in that case the 20 said body is mounted immediately upon the center sills, and in order to distribute the load and pressure to the side sills also there may be interposed between the said side sills and the body or center sills the transom 25 in any 25 of a variety of ways, (see, for examples, Figs. 1 and 4,) and the braces 26 may project from these transoms to the inverted apexial end of the body, as indicated in Fig. 4.

Plate or sheet metal or other equivalent 30 metal of sufficient strength and stiffness and pressed to shape may be used in the construction of most or all of the parts herein shown and described, although the center sills may be rolled and the various brackets and bearings may be castings.

By the construction of underframe herein described I obtain great strength and stiffness and also great load-sustaining capacity with facility of repair.

40 While the underframe herein shown and described is designed especially for dump-ballast cars, I do not limit its use to that one character of car.

The features of the herein-described and 45 shown underframe not herein specifically claimed are reserved for my application for patent filed August 21, 1901, Serial No. 72,832, which also is a division of my application, Serial No. 40,649, hereinbefore referred to, 50 and other features herein in part or otherwise shown and described are reserved to the afore-

said original patent application and any other division thereof wherein they are claimed.

What I claim is—

1. The combination of side sills and bolsters, each bolster comprising a pair of parallel channeled beams extending continuously between and secured to the side sills, with a bolster cover-plate extending from side to side of the car and from the inner 60 edge of the bolster outwardly toward the end of the car and of greatest width in the plane of the draft-rigging, and a correspondingly-shaped cover-plate applied to the lower side of the bolster and extending from side bearing to side bearing and also projecting outwardly toward the end of the car and of greatest width in the plane of the draft-rigging, substantially as described. 65

2. The combination of sidesills, continuous 70 transverse bolsters extending from side sill to side sill and secured to said side sills, cover-plates for said bolsters applied above and below them and of greatest width in the plane of the draft-rigging, end sills, and oblique 75 braces interposed between the end sills and the said bolsters, substantially as described.

3. A bolster for underframes, composed of continuous parallel channeled beams of a 80 length to extend between and be secured to the side sills of the car, a top cover-plate riveted to the upper flanges of the beams and of greatest width in the plane of the draft-rigging, substantially triangular gusset-plates riveted to the flanges of the inner beam, and 85 a bottom cover-plate also of greatest width in the plane of the draft-rigging, substantially as described.

4. A body-bolster, of box-girder type, composed of parallel channeled beams of length 90 sufficient to extend continuously from side sill to side sill, and top and bottom cover-plates, and having its lower portion dished at opposite ends to provide clearance for the truck-wheels, substantially as described. 95

In testimony whereof I have hereunto set my hand this 16th day of August, A. D. 1901.

JOHN M. HANSEN.
